UNITED STATES PATENT OFFICE

GERALD POULTON, OF BROMLEY, ENGLAND

LOOSE LEAF BINDER OR FILING COVER

Application filed June 10, 1930, Serial No. 460,266, and in Great Britain November 28, 1929.

This invention has reference to improvements in loose leaf binders or filing covers of the kind in which fasteners, secured to or passed through one of two covers, and in the form of tongues of flexible metal, pass through perforations in the loose leaves to be bound together, and through a strip or flap of material, or through the opposite cover, over which their free end portions are bent to hold the sheaf of leaves in place.

An object of the present invention is to provide for use with fasteners such as referred to, washers so constructed that the bent over free end portions of the fasteners, after being passed through the leaves and a strip or flap, or opposite cover, can be engaged therewith and become firmly held in place thereby but in a readily detachable manner so as to admit of the addition or the removal of leaves as may be desired, the arrangement being such that when the free end portions of the fasteners are bent over and engaged with the washers, the leaves will be firmly and neatly held together.

The invention also has for its object so to construct the washers that when any desired number of leaves have been assembled and held together, they can be permanently clamped together by the fasteners and washers, of which there will usually be two, so as in effect to form a bound volume of neat and advantageous form.

To attain these objects, each washer, made of thin sheet material, for instance, thin sheet metal, is provided with oppositely arranged projections or fingers that overlap the washer and have their free ends spaced at a distance apart less than the width of the fastener to be used therewith, and spaced at a distance apart at their roots rather more than the width of the fastener, so that the free end portion of the fastener, after being passed through a sheaf of leaves, can be bent over the washer and by slightly bending or twisting it sideways, can be passed first under one of the fingers and then under the other finger so as to become held down in position thereby, this operation being reversed when it is desired to detach the fastener from the wash-

er to admit of the addition or removal of one or more leaves.

To admit of any desired number of leaves, after being bound together in the manner described, being permanently clamped together to form a complete volume, the fingers on each washer are flattened down under pressure, upon the portion of the fastener below them. In this way the sheaf of leaves is firmly clamped or locked together to form a neat volume from which leaves cannot readily be removed, though they could be removed by lifting the fingers to free the fasteners, though the trouble this would involve would usually deter any one needlessly, or without sanction, attempting to remove one or more leaves. The washers may each be formed with a slot through which the free end portion of a fastener can be passed before being bent down for engagement with the holding portions of the washer.

Washers such as described, adapted for use in the manner set forth, can be constructed in various ways.

In the accompanying illustrative drawings, Fig. 1 shows in plan and Figs. 2 and 3 in elevation at right angles to one another, one construction of washer according to the invention. Fig. 3^a shows the washer fixed to a flap, Figs. 4, 5 and 6 are respectively similar views to Figs. 1, 2 and 3 showing a modified construction. Figs. 7 and 8 show, in elevation, at right angles to one another, and Fig. 9 in plan, one construction of flexible metal fastener according to the invention. Fig. 10 shows in elevation, a modified construction of fastener, and Figs. 11 and 12 show respectively in plan and elevation, a construction of washer for use therewith. Fig. 13 shows in elevation a further modified construction of fastener. Fig. 14 shows a loose leaf binder embodying the invention with one cover thereof open and Fig. 15 is a section on the line 15—15 of Fig. 14. Fig. 16 is a detail view showing a modification.

In the example shown in Figs. 1, 2 and 3, each washer is made by stamping in a rectangular shaped piece of thin sheet metal 1, a double truncated longitudinally extending wedge-shaped hole 2 (Fig. 1) and bending 100

to one side of the piece of metal, the two opposite angular shaped portions of the metal left at opposite sides of the hole, to form figures 3, 3^a, inclined to the face of the piece of metal 1 and to one another and having their apices at a distance apart less than the width of the fastener to be passed therethrough, the width of the hole 2 at its opposite ends, and therefore the distance apart of the roots of the fingers 3, 3^a, being slightly greater than the width of the flexible metal fastener with which the washer is to be used.

According to the modified construction shown in Figs. 4, 5 and 6, each washer consists of a piece of thin sheet metal 1 formed with two opposite edge portions, preferably of rectangular shape as shown, which are bent over the intermediate portion so as to form two opposed fingers 1^a 1^b, the free edges or apices of which are spaced at a distance apart less than the width of the fastener to be engaged therewith in the manner hereinbefore described. In this case the fingers may be inclined to or be more or less parallel with the intermediate portion of the washer. They are shown inclined thereto.

In each case, the washer 1, may as shown, be formed, as by punching, with a transverse slot 4 through which the free end portion of the associated fastener can be passed before being bent down and engaged with the fingers of the washer.

As it will usually be desirable to secure two such washers, at a suitable fixed distance apart, to a strip or flap of cardboard or other material, or to one of the covers of the binder, that is to bear against the sheaf of leaves at one side thereof and through which two fasteners pass, each washer may be provided on the side thereof opposite to that provided with the fingers, with projections that can be passed through slits in the said strip or flap or cover and be clinched over the opposite side thereof so as to fix the washer permanently to the strip or flap, or cover.

For this purpose, when the washer is made in the manner first hereinbefore described (Figs. 1, 2 and 3), the piece of metal stamped out of each washer 1 to form the aforesaid double truncated wedge-shaped hole 2 therein, may be slit at the centre of its length to form two truncated wedge-shaped portions 5, 5^a that are integral with the washer and are bent at right angles to the washer at the wide ends of the hole 2 therein and to the opposite side of the washer to that from which the oppositely arranged fingers 3, 3^a extend, so as to form fastening projections for the purpose set forth. Fig. 3^a shows how the portions 5, 5^a of the washer can be passed through a flap or cover A and be clinched over the same to fasten the washer thereto. Or the piece of metal from which a washer of either of the kinds hereinbefore described is made, may, and as shown in Figs. 4, 5 and

6, be provided with fastening projections, for the purpose mentioned, by stamping out portions 6 of the opposite ends thereof and bending the resulting portions at right angles to the washer as shown.

The flexible metal fasteners for use with washers constructed as described, can be of various kinds. Each fastener may, as shown in Figs. 7, 8 and 9, consist of a single narrow strip of sheet metal 7 connected at one end to a piece of sheet metal 8, constituting a base piece, that is formed, by stamping, with a double truncated wedge-shaped hole 9, the metal from which is slit centrally of its length and the resulting two truncated wedge-shape portions 10 of metal bent at right angles to the base piece so that they can be passed through corresponding slits in a strip or flap of cardboard or other material connected to one of the covers of the binder and clinched over the opposite side thereof to securely fix the base piece to the strip or flap, the narrow strip 7 of metal connected to the said base piece 8 being then bent at right angles to the latter to form a fastener for passage through loose sheets and a washer such as hereinbefore described.

Or, as shown in Fig. 10, the fasteners employed may each be of the kind having two narrow parallel limbs 7^a, 7^b connected at one end to a base piece 8^a and adapted, after being passed through loose leaves and a washer constructed as hereinbefore described, to have their free end portions separated and turned down in opposite direction. In this case, each washer may, as shown in Figs. 11 and 12, be formed with two holes with two sets of oppositely inclined fingers 3, 3^a of the kind hereinbefore described and with a transverse slot 4 between them to receive the two limbs 7^a, 7^b of the fastener, so that the free end portions of such limbs can be turned down in opposite directions and each of them be engaged with one of the sets of oppositely inclined fingers 3, 3^a, in the manner hereinbefore described for a single set of fingers.

The construction of the washers and fasteners may be such as to prevent the free end portion of each fastener when inserted in its washer, from being withdrawn endways therefrom. For this purpose, as shown in Fig. 13, each fastener may be formed with undulating or notched edges 7^c and each washer with two ribs or projections, 1^c, 1^d (Figs. 1 and 4) with which the undulating or notched edges of the fastener can be engaged when the fastener is inserted between them after having been inserted under the fingers 3, 3^a, on the washer.

The invention can be applied to loose leaf binders of various kinds. It can however advantageously be applied to a loose leaf binder of the kind shown in Figs. 14 and 15 and comprising a flexible back 11 having bent

over portions or flaps 11^a, 11^b that are slotted at 11^c to receive the fasteners 7, and covers 12 and 13 each of which is formed with a narrow marginal portion or flap 12^a or 13^a 5 through which the fasteners 7 can pass without interfering with the covers which are thus free to be opened about an edge 12^b or 13^b, coincident with the back of a sheaf of leaves 14 held between the bent over portions 10 11^a, 11^b of the flexible back 11. The leaves 14 are formed with corresponding slots for the passage of the fasteners 7. Washers of one or other of the kind hereinbefore described are secured to the top of the flap 13^a 15 of the cover 13 as shown, and the portions 8 connected to the fasteners 7 are secured to or bear against the lower side of the flap 12^a of the cover 12. The flap 11^b of the flexible back 11 may be secured, as by an adhesive, 20 to the flap 12^a of the front cover 12 as in Fig. 15, or it may be in one piece with the flap 12^a of the front cover 12, the said flaps 11^b and 12^a being formed by suitably folding the material constituting the back 11, cover 12 and 25 flaps 11^b and 12^a, as indicated in Fig. 16. The flexible back 11 may advantageously be adapted, as by scoring, corrugating or creasing it from top to bottom, in known manner, and as shown at 11^a in Fig. 14, to admit of 30 the flaps 11^a, 11^b that bear against the opposite sides of a sheaf of leaves 14 between them, assuming positions at right angles to the intermediate part 11 with sheaves of leaves of different thickness, the slots 11^c in the flaps 35 11^a of the flexible back 11 are made long, as shown, so as to admit of the back accommodating itself to sheaves of leaves of varying thickness without being affected by the fasteners which pass through the slots in its flap 40 portions 11^a, 11^b.

What I claim is:—

1. For use with a loose leaf binder provided with a flexible flat metal fastener, a washer formed of thin sheet material and 45 having therein a single transversely arranged slot, and at one side thereof, two oppositely inclined fingers arranged directly opposite each other and adjacent to said slot, each finger being normally inclined to said washer at an angle less than a right angle for the purpose set forth.

2. For use with a loose leaf binder provided with a flexible flat metal fastener, a washer formed of thin sheet material and 50 having therein a single transversely arranged slot, and at one side thereof, two oppositely inclined fingers arranged directly opposite each other and adjacent to said slot, each finger being normally inclined to said washer at an angle of about 45° for the purpose set forth.

3. For use with a loose leaf binder provided with a flexible flat metal fastener, a washer formed of thin sheet material and 55 having therein a single transversely arranged

slot, and also a longitudinally extending hole, and extending from opposite sides of said hole, two oppositely inclined fingers arranged directly opposite each other and adjacent to said slot, each finger being normally inclined to said washer at an angle less than a right angle, for the purpose set forth. 70

4. For use with a loose leaf binder provided with a flexible flat metal fastener, a washer formed of thin sheet material and 75 having therein a single transversely arranged slot, and also a longitudinally extending hole, and extending from opposite sides of said hole, two oppositely inclined fingers arranged directly opposite each other and adjacent to said slot, each finger being normally inclined to said washer at an angle of about 45°, for the purpose set forth. 80

5. For use with a loose leaf binder provided with a flexible flat metal fastener, a washer formed of thin sheet material having 85 therein, intermediate of its length, a transversely arranged slot and at each side of said slot, a longitudinal hole and adjacent to said slot and at each side thereof and extending from the opposite longitudinal edges of the corresponding longitudinal hole, two oppositely inclined fingers arranged directly opposite each other, each finger being normally inclined to said washer at an angle less than a right angle, for the purpose set forth. 90

6. For use with a loose leaf binder provided with a flexible flat metal fastener, a washer formed of thin sheet material having 95 therein, intermediate of its length, a transversely arranged slot and at each side of said slot, a longitudinal hole and adjacent to said slot and at each side thereof and extending from the opposite longitudinal edges of the corresponding longitudinal hole, two oppositely inclined fingers arranged directly opposite each other, each finger being normally inclined to said washer at an angle of about 45°, for the purpose set forth. 100

7. In a loose leaf binder comprising oppositely arranged binding members and flexible flat metal fasteners engaged with one of said members and adapted to be passed through loose leaves between said members and the second member and to be bent over the latter member, the combination with each fastener of a washer formed of thin sheet material having a single transversely arranged slot therein through which the corresponding fastener can be passed and provided with two oppositely inclined fingers arranged directly opposite each other and adjacent to said slot, and having their free ends spaced at a distance apart less than the width of the corresponding fastener, each finger being normally inclined to said washer at an angle less than 90°, for the purpose set forth. 115

8. In a loose leaf binder comprising oppositely arranged binding members and flexible flat metal fasteners engaged with one of 120

said members and adapted to be passed through loose leaves between said members and the second member and to be bent over the latter member, the combination with each 5 fastener of a washer formed of thin sheet material having a single transversely arranged slot therein through which the corresponding fastener can be passed and provided with two oppositely inclined fingers arranged directly opposite each other and adjacent to 10 said slot, and having their free ends spaced at a distance part less than the width of the corresponding fastener, each finger being normally inclined to said washer at an angle about 45°, for the purpose set forth.

9. A loose leaf binder according to claim 7, wherein the washer is formed with a transversely arranged slot through which the corresponding fastener can be passed, with a 20 longitudinal hole and with a single pair of oppositely inclined fingers arranged adjacent to said transverse slot and having their free ends spaced at a distance apart less than the width of the corresponding fastener, each 25 finger extending from one edge of said longitudinal hole and normally inclined to the fastener at an angle of about 45° to said washer, for the purpose set forth.

10. A loose leaf binder comprising oppositely arranged binding members between 30 which loose leaves can be clamped, two flexible flat metal fasteners secured to one of said members and each comprising two parallel limbs adapted to be passed through loose 35 leaves and the second member and to be bent in opposite directions over said second member and two washers attached to said second member and each formed intermediate of its length with a transverse slot through which the two limbs of the corresponding fastener 40 can be passed and provided at each side of said slot and adjacent thereto with a pair of oppositely inclined fingers arranged directly opposite each other and having their free 45 ends spaced at a distance apart less than the width of the limb of the corresponding fastener that is to be engaged therewith, each finger being normally inclined to said washer at an angle less than 90°, for the purpose set forth.

11. A loose leaf binder according to claim 10, wherein each finger is normally inclined to said washer at an angle of about 45°, for the purpose set forth.

55 Signed at London, England, this 20th day of May, 1930.

GERALD POULTON.
